CLAIM

We claim the ornamental design for an ironing board, as shown and described.

DESCRIPTION

FIG. 1 is a perspective view of an ironing board showing the new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a perspective view of the ironing board showing an alternate configuration with the sleeve board unfolded;

FIG. 9 is a front elevation view thereof;

FIG. 10 is a rear elevation view thereof;

FIG. 11 is a left-side elevation view thereof;

FIG. 12 is a right-side elevation view thereof;

FIG. 13 is a top plan view thereof; and,

FIG. 14 is a bottom plan view thereof.

The broken line represent portion of the ironing board that form no part of the claimed design.
